UNITED STATES PATENT OFFICE.

ANTOINE VÉRICEL, OF NEW YORK, N. Y.

DESIGN FOR A DISPLAY-STAND.

53,387.

Specification for Design.

Patented May 27, 1919.

Application filed March 12, 1919. Serial No. 282,217. Term of patent 3½ years.

To all whom it may concern:

Be it known that I, ANTOINE VÉRICEL, a citizen of France, residing at New York, borough of Manhattan, in the county and State of New York, have invented a new, original, and ornamental Design for a Display-Stand, of which the following is a specification, reference being had to the accompanying drawings, forming part thereof.

Figure 1 is a view in elevation of a display stand showing my new design; Fig. 2 is a side elevation thereof; and Fig. 3 is a top plan view of the same.

I claim:

The ornamental design for a display stand, as shown.

ANTOINE VÉRICEL.
